AUTOMATIC HAT FORMER

Herbert F. Fitch, Norwalk, Conn.

Application December 11, 1945, Serial No. 634,200

10 Claims. (Cl. 19—148)

1

This invention relates to mechanism for forming felt hats, and has for an object to provide a device which will automatically perform the various operations necessary in forming a hat body, in the proper sequence.

It is also an object to provide a hat former in which the hat is formed upside-down, as distinguished from the usual practice of forming it in the upright position.

Further objects are to provide means for automatically removing the formed hat body from the cone without removing the cone from the former, to reduce handling of the formed hat body and therefore reducing breakage, and to reduce variation in the lay of the fur on the cone and thus produce a body of more uniform thickness.

With the foregoing and other objects in view, I have devised the construction illustrated in the accompanying drawing forming a part of this specification. It is, however, to be understood the device is not limited to the specific details of construction and arrangement shown, but may embody various changes and modifications within the scope of the invention.

In these drawings:

Fig. 1 is a vertical longitudinal section and partial side elevation of the machine shown somewhat diagrammatically, the parts being shown in position just after the spray to the formed cone has been cut off;

Fig. 2 is an end view of the feeder portion of the device looking from the right of Fig. 1;

Fig. 3 is a section through the former showing the spray device;

Fig. 4 is a section through the former showing the hat body receiver;

Fig. 5 is a detail section of the mounting for the spraying mechanism for the receiver;

Fig. 6 is a vertical section of the former (shown diagrammatically) and sections showing position of the related devices during the hat forming operation;

Fig. 7 is a similar view showing the positions of the related devices during the spraying operation;

Fig. 8 is a similar view showing the devices in position for removing the formed body from the cone, and

Fig. 9 is a section indicating the type of automatic control for the various operations.

As above suggested, this device performs all the operations of forming the hat body automatically, in the proper sequence, and it comprises a former 10 and a feeder 11 for feeding the

fur to the former. This former includes a casing 12 in which is mounted a perforated forming cone 13, but in this case the cone is mounted in the inverted position, as indicated, instead of in the usual upright position. During the forming operation it is rotated about its vertical axis by any suitable mechanism, indicated diagrammatically at 14, and the interior of the cone is connected with the usual suction pipe 15 leading to a suction fan 16 driven constantly by any suitable means, not shown. In the suction pipe is a control valve or damper 17 which is controlled automatically by suitable mechanism. In the present case it is shown diagrammatically as operated by a fluid pressure piston 18. The inlet to the former indicated at 19 is the outlet or discharge from the feeder 11. This feeder may be of any suitable type but is preferably similar to that disclosed in my prior Patent No. 1,598,429, issued August 31, 1926. This feeder comprises a feed apron or conveyor 20 leading to a pair of feed rolls 21 for a picker 22 at the lower end of a chute 23 leading to the foraminous drum 24. This may be a wire mesh drum and is of suitable size to retain on about one-half of its surface the necessary amount of fur for one hat body. At the opposite side of this drum from the inlet 23 is a transfer roll or cylinder 25 for transferring fur from this drum to the feed rollers 26 of a picker 27 in front of a drum 28 for throwing fur from the picker through the inlet 19 to the former. The two pickers 22 and 27 are operated continuously but the conveyor 20 and the drum 24 are operated alternately, and each is stationary while the other is operating.

This device may be driven from any suitable means, but is shown as driven from a main drive shaft 29 driven by a suitable motor 30 through a suitable belt drive 31. On the shaft is a suitable pulley 32 for driving the two pickers 22 and 27 through suitable belt drives 33, 34 and 35. Also on the shaft is a pulley 36 for driving the feed apron 20 through a suitable belt drive 37, and another pulley 38 on the main shaft drives the drum 24 through the belt 39 to a short shaft 40, and a belt 41 to the shaft 42 for the transfer roll 25. There is a drive 43 from this shaft to a pulley or sprocket 44 for driving the drum 24, and there is also a drive from the shaft of this drum by a pulley 45 through a belt 46 to a control disc 47. This drive 46 is so proportioned that the control disc 47 will make one revolution for about two-thirds revolution of the drum 24. This disc 47 has in its periphery a notch 48 to receive 55 at certain times the upper end of a control rod 49

mounted to slide vertically in suitable guides 50. At its lower end this rod rests on a lever arm 51 on a shaft 52 carrying a forked lever 53 connected to a sliding rod 54 connected by an arm 55 to a pair of clutch cones 56 and 57. These cones are splined to slide longitudinally on the main drive shaft 29 and are adapted to engage similar internal cones on the pulleys 38 and 36 respectively for driving these pulleys at the proper time, the pulleys being otherwise loose on the shaft. A suitable spring 58 tends to shift the rod 54 and the parts connected therewith to the right as viewed in Fig. 2 and retain the cone 57 in engagement with the pulley 36.

On the vertical slidable rod 49 is an arm 59 leading to a piston 60 operated at the proper time by suitable fluid pressure to draw the rod 49 downwardly, as will presently be described. Also mounted on the rod 49 is a trip lug 61 adapted to engage a trip lever 62 for operating an electric switch 63. This switch is a control switch for the control of timing motor 64 connected to the switch 63 through any suitable leads 65 and a source of supply current, not shown, at 66. This motor operates a timing or control mechanism 67. This comprises a series of cams for controlling either a series of air or fluid pressure control valves or a series of electric control switches. In the present case it is shown as operating a series of air valves to control various devices for controlling the forming operations, but it will be understood if electric controls are used there would be electric switches or operating means for them. As indicated, the motor 64 through a suitable drive 68 operates a shaft 69 on which are a series of cams, one of which is shown at 70 in Fig. 9, of any suitable shape to operate through a follower rod 71, a control valve 72 controlling the supply of air at given times through a suitable supply pipe 73 from any suitable source of air pressure, not shown, through connecting pipes 74 and 75 to various mechanisms. Fig. 9 happens to be the valve control 72 for piston 76, but it will be understood this is shown merely as an example, to illustrate the type of control used and that there will be a similar cam on shaft 69 for each of the other control valves and each shaped according to the operation desired for its particular valve and the device controlled by it. The follower 71 is kept against the cam and the valve is operated in one direction by a spring 71a.

As shown in Fig. 1, the valve 72 is connected by pipes 74 and 75 with the cylinder of a piston 76 operating an automatically controlled sprayer 77 which may be moved through an opening 78 in the side of the former casing or housing 12 to a position adjacent the cone 13 for spraying the body formed on the cone at given times, as will presently be described. This may be any suitable type of sprayer, but is preferably flat, of a width of six or eight inches, and provided with a series of fine openings 79 for a fine spray supplied through the pipes 80 and 81 from a suitable source of supply, not shown, and controlled by the valve 82 of the control device 67, pipe 81 being connected to the pipe 80 by a flexible connection 83 to permit in and out movements of the sprayer 77. A drip pan or catcher 84 is preferably provided under the sprayer to catch any drip from the sprayer and it is mounted on the pipe 80 to move with the sprayer. The opening 78 in the former housing 12 is closed during the forming operation by a door 85 which is

operated automatically by movements of the sprayer 77, as indicated more clearly in Fig. 3. This door or closure is mounted to slide to and from a position over the opening 78 by any suitable mechanism operated by movements of the sprayer 77. That shown comprises a bell crank lever 86 pivoted at 87, one arm 88 of which is connected to the door by a link 89 and the other arm 90 is connected to the supply pipe 80 by a link 91. As the sprayer is moved toward the opening by the piston 76 the connection will slide the door or closure from the opening to the dotted line position, permitting the sprayer to move into the position shown in Figs. 1 and 7 adjacent the former cone 13. Movement in the opposite direction will cause the door to close so that the door opening is closed during the forming operation and when the suction is on the cone 13.

The draft or suction in the pipe 15 is controlled by the damper 17 and the piston 18. The operation of this piston is controlled by the valve 92 from a suitable cam on the shaft 69 through the supply pipes 93. Within the top of the cone 13 is a perforated air blast pipe 94 which is connected by a pipe 95 through the control valve 96 with the source of supply, not shown, this valve being also controlled by a suitable cam on the shaft 69. This air blast is used to loosen the formed hat body on the cone 13 at the proper time, so that it will drop off of the cone by its own weight. The piston 60 operating the control rod 49 of the feeder is controlled by the valve 97 through the pipe 98, this valve also being controlled by a suitable cam on the shaft 69.

Means is provided for catching the hat body as it drops from the cone 13. This is the receiver 99 which during the forming operation is outside the former 10, but after the hat body has been properly formed and is ready for removal, it is shifted to a position in the former under the cone 13, as shown in Figs. 1 and 8. Its motion to and from this position is controlled by piston 100 controlled from the control device 67 by a valve 101, which, like the other valves, is controlled by a suitable cam on the shaft 69, suitable pipes 102 connecting this valve with the cylinder of the piston 100. The receiver disc or plate 99 is mounted on a pivot arm 102 pivoted on a suitable support 103 so as to swing to carry the receiver 99 through the opening 104 in the former housing 12 to and from its position under the former cone 13. The arm 102 is on a shaft pivoted in the support 103 which is connected to the piston 100 by a flexible strap 105. A coiled spring 106 tends to swing the arm 102 counter-clockwise, as viewed in Fig. 4, or that is, to maintain the receiver 99 in the full line position of this figure, outside the former. If pressure is applied to the piston 100 it will be shifted to the right in Fig. 1 and unwind the strap 105 from the shaft, thus swinging the receiver 99 through the opening 104 to the dotted line position under the cone 13. When the pressure is released from the piston, or the piston is operated in the opposite direction, spring 106 will swing the receiver 99 outwardly through this opening so that any hat body, indicated at 107, which may have been dropped from the former cone 13 onto this receiver, may be removed by the operator. The closure 108 for the opening 104 is connected with this arm 102 so as to be operated automatically on operation of the receiver. In the arrangement shown, the closure is pivoted at 109 and is connected by an arm 110 through a link 111 with the rod 102 so that as the receiver 99 is swung

toward the former, the closure is swung inwardly to the dotted line position, and then as this receiver is swung outwardly again, the closure is automatically closed.

The operation is as follows:

We will assume the upper end of the rod 49 is in the notch 48 in the control disc 47, as shown in Fig. 11. In this position the perforated drum 24 is stationary and clutch 57 (Fig. 2) is in engagement with the corresponding element of the pulley 36 and the feed apron 20 is operating. The proper amount of fur for a hat had been placed by the weigher on this apron, and is thus fed by it to the picker 22 and blown by the picker onto the drum 24. During this time the switch 63 is closed so that the control motor 64 is operating. At completion of the transfer of the fur on the apron 20 to the drum 24 the control valve 97 operates to operate the piston 60 to draw the control rod 49 downwardly. This opens the switch 63, stopping the motor 64, and it also removes the upper end of the rod 49 from the notch in the disc 47. At the same time this movement of the rod operates the lever 51, it shifts the clutch members 56 and 57 to the left, as shown in Fig. 2, shifting cone 57 away from the pulley 36, and thus stops operation of the apron 20, but it moves the clutch 56 into engagement with the pulley 38 and starts operation of the drum 24. The disc 47 rotates with the drum 24 through the drive 46, and as soon as the disc 47 starts to rotate the upper end of rod 49 rests against the rim of this disc and thus the rod 49 is held in its lower position by the disc. As the drum 24 rotates, the fur which has been collected on it is fed by the transfer roll 25 to the picker 26, and thrown by the drum 28 through the opening 19 into the dome of former 10. During this operation the elements are in the position of Fig. 6, the cone 13 being rotated, the damper 17 being open and the fur being drawn to and deposited on the cone by the action of the suction fan 16. As in this operation no other opening to the former dome 10 is open, the fur is uniformly deposited on the rotating cone 13, giving a hat body of uniform thickness and condition throughout. This fur is fed to the former during about two-thirds revolution of the drum 24, but the drive 46 is so proportioned that the control disc 47 is given a complete revolution, and at the end of this time the notch 48 again comes into alignment with the end of the rod 49, so that the spring 58 (Fig. 2) is now free to shift the rod 54 to the right and operate the lever 51 to lift the rod 49 to seat its upper end in the notch 48. This releases the clutch 56 from the pulley 38 and stops operation of the drum 24. During the time of operation of drum 24 the apron 20 has been stopped and the weigher has placed another batch of the proper amount of fur for another hat on this apron. Shifting of the clutch 57 to the right of Fig. 2 again causes it to engage the pulley 36 to operate the apron 20 and feed this additional batch of fur through the picker 22 to the drum 24 for the next hat forming operation.

When the rod 49 was shifted upwardly, however, it permitted the switch 63 to close to start the control motor 64. This now through the operating cam for this valve on the shaft 69 operates the valve 72 to operate the piston 76 to shift the sprayer 17 into the former through the opening 18 to the position of Figs. 1 and 7. When it reaches this position the cam for the valve 82 opens it to supply water through the pipe 81 to the sprayer, causing a fine spray to be ap-

plied to the hat body on the rotating cone 13. After the proper amount of spray has been accomplished, this valve 82 cuts off the spray and the valve 72 then operates to cause the sprayer 17 to be drawn out of the former to its position of Fig. 6. Then the valve 92 is operated by its cam to operate the piston 48 to close the draft control valve 11 and cut off the draft, as shown in Fig. 8, and also in Fig. 1. Then the control valve 101 is operated by its cam to operate the piston 100 to swing the hat receiver 99 through the door opening 104 to the position of Figs. 1 and 8 under the revolving cone 13. Then the valve 96 is operated by its cam to cause a blast of air through the perforated pipe 94 which loosens the edge of the hat body on the cone 13 so that this body drops down onto the hat receiver 99, as indicated at 107 (it is to be understood that before this happens the sprayer 17 is withdrawn from the position within the former indicated in Fig. 1). The cam in the control valve 101 then causes the piston 100 to be shifted in the opposite direction, permitting the spring 106 (Fig. 5) to swing the receiver 99 carrying the hat body out of the former to the full-line position of Fig. 4, closing the door 108 and leaving the whole apparatus in condition for a subsequent hat body forming operation. The control valve 92 is then operated by its control cam to open the draft control 11 to permit the suction on the former cone 13 to begin again, and then the control valve 97 is operated by its cam to shift the control rod 49 downwardly again and thus cause the whole cycle to commence again for the forming of the next hat body. While this next hat body is being formed through this same cycle, the operator may remove the body 107 from the receiver 99, and it may be given to whomever is to perform the succeeding operations of shrinking, and so forth.

It will be seen from the above that the operation of forming the body is automatic from the feed apron 20 to the removal of the formed body from the receiver 99. With this device no coner is necessary, and only one cone is used and this is not handled as it remains in the former, hence there is no cone breakage and no cover is required for the cone. No tip or side cloths are required and there is no tub or dipper required. There is also practically total elimination of finger strings, and there is less variation in the lay of the fur on the cone, as the doors or openings to the former are all closed when the fur is being deposited on the cone. There are no rolls, as the hat is formed upside-down. Excess water from the sprayer 17 is caught by the tray or drip pan 84 so there is no accumulation of excess moisture in the former, and the machine is also mechanically less complicated than those presently employed, and as the hat is handled less there is less breakage of the hat bodies. No coner is necessary as the hardener can lift the hat body directly from the hat receiver.

Having thus set forth the nature of my invention, what I claim is:

1. In a hat forming machine of the character described, a former comprising a hood, an inverted perforated cone in said hood, means for rotating the cone about its axis, a suction means connected with the interior of the cone, a feeder for discharging blown fur into the hood to be deposited on the cone by the suction, an automatic control device including a control for the suction, a control means for controlling operation of the feeder, and means controlled by the feeder con-

trol for controlling the operation of the automatic control device.

2. In a hat forming machine of the character described, a former comprising a hood, an inverted perforated cone suspended in the hood, means for rotating the cone about its axis, a suction means connected with the interior of the cone, a feeder for feeding blown fur into the hood for deposit on the cone, a perforated blast pipe within the upper portion of the cone, means for supplying fluid pressure to said pipe to loosen a formed hat body on the cone so that it will drop therefrom, an automatic control device including a control for each of the suction and the means for supplying fluid pressure to said pipe, means for operating the feeder including a control means, and means controlled by the feeder control for controlling the operation of the automatic control device.

3. In a hat forming machine of the character described, a former comprising a hood, an inverted perforated cone suspended in the hood, means for rotating the cone about its axis, a suction means connected with the interior of the cone, a feeder for feeding blown fur into the hood for deposit on the cone, means for spraying a formed hat body on the cone, a perforated blast pipe within the upper portion of the cone, means for supplying air pressure to said pipe to loosen the hat body on the cone so it will drop from the cone, an automatic control device including a control for each of the suction, the spraying means and the air supply, means for operating the feeder including a control means, and means controlled by the feeder control for controlling the operation of the automatic control device.

4. In a hat forming machine of the character described, a former comprising a hood, an inverted perforated cone suspended in the hood, means for rotating the cone about its axis, a suction means connected with the interior of the cone, a valve for controlling the suction on the cone, a feeder for feeding blown fur into the hood for deposit on the cone, a sprayer for spraying a formed hat body on the cone and movable to and from a spraying position near the cone, a perforated air discharge pipe in the cone adjacent the upper end thereof in position to loosen the hat body on the cone, control means for each of the valve, the sprayer and the air blast, an automatic control for each of said controls arranged to operate them in certain timed relation, means for operating the feeder including a control means, and means controlled by the feeder control for operating the automatic control in certain timed relation with the feeder.

5. In a hat forming machine of the character described, a former comprising a hood, an inverted perforated cone suspended in the hood, means for rotating the cone about its axis, a suction means connected with the interior of the cone, a feeder for feeding blown fur into the hood for deposit on the cone, a perforated blast pipe in the upper part of the cone, means for supplying air under pressure to said blast pipe to loosen a hat body on the cone, a sprayer movable to and from a position adjacent the cone, a receiver for the hat body movable between a position outside the hood to a position in the hood under the cone, an automatic control device, control means operated by said device for each of the suction means, the sprayer, the air blast, the receiver and the operation of the feeder and arranged to operate them in certain timed relation with each other, and means controlled by the feeder control for oper-

ating the automatic control device in certain timed relation with the feeder.

6. In a hat forming machine of the character described, a former comprising a hood, an inverted perforated cone suspended in the hood, means for rotating the cone about its axis, a suction means connected with the interior of the cone, a feeder for feeding blown fur into the hood for deposit on the cone, a sprayer movable to and from a position adjacent the cone, means for loosening a formed body on the cone so that it will drop from the cone, a receiver for said body movable between a position outside the hood and a position under said cone to receive the hat body, an automatic control device including a control for each of the suction, the sprayer, the hat body loosening means, the hat receiver and the operation of the feeder, means for operating the feeder, and means controlled by the feeder control for controlling the operation of the automatic control device.

7. In a hat forming machine of the character described, a former comprising a hood, an inverted perforated cone suspended in the hood, means for rotating the cone about its axis, a suction means connected with the interior of the cone, a feeder for feeding blown fur into the hood for deposit on the cone, means for loosening a formed hat body on the cone so that it will drop from the cone, a receiver for said body movable between a position outside the hood and a position under the cone to receive the hat body from the cone, means for operating the receiver, an automatic control device including a control for each of the suction, the hat body loosening means and the receiver operating means, means for operating the feeder, a control means for the feeder operating means, and means controlled by the control for the feeder operating means for controlling the operation of the automatic control device.

8. In a hat forming machine of the character described, a former comprising a hood, an inverted perforated cone suspended in the hood, means for rotating the cone about its axis, a suction means connected with the interior of the cone, a feeder for feeding blown fur into the hood for deposit on the cone, a sprayer movable to and from a position adjacent the cone through an opening in the hood, a closure for said opening, a connection from the sprayer to the closure to automatically shift the closure from the opening as the sprayer moves toward the cone and to shift the closure to the opening as the sprayer is shifted from the cone to a position outside the hood, and means for shifting the sprayer.

9. In a hat forming machine of the character described, a former comprising a hood, an inverted perforated cone suspended in the hood, means for rotating the cone about its axis, a suction means connected with the interior of the cone, a feeder for feeding blown fur into the hood for deposit on the cone, means for loosening a formed hat body on the cone so that it will drop from the cone, a receiver for said hat body movable through an opening in the hood between a position outside the hood and a receiving position under the cone, a closure for said opening, a connection between the receiver and the closure to shift the closure from the opening as the receiver is shifted to the receiving position and to shift the closure to the opening as the receiver is removed from the hood, and means for shifting the receiver between said positions.

10. In a hat forming machine of the character

described, a former comprising a hood, an inverted perforated cone suspended in the hood, means for rotating the cone about its axis, a suction means connected with the interior of the cone, a feeder for feeding blown fur into the hood for deposit on the cone, means for loosening a formed hat body on the cone so that it will drop from the cone, a receiver for the hat body movable between a position outside the hood and a receiving position under the cone, means for operating the receiver, means for controlling the suction, means for operating the feeder, a control means for the feeder operating means, and control means for the suction, the hat body

loosening means and the receiver controlled by the feeder control means.
